[57] CLAIM

The ornamental design for an infant carrier, as shown and described.

DESCRIPTION

FIG. 1 is a perspective view of an infant carrier, showing a first embodiment of my new design;

FIG. 2 is a top plan view of the infant carrier of FIG. 1; FIG. 3 is a right side elevational view of the infant carrier of FIG. 1, the left side being a substantial mirror image except for the protruding tongue;

FIG. 4 is a bottom plan view of the infant carrier of FIG. 1;

FIG. 5 is a rear elevation of the infant carrier of FIG. 1; FIG. 6 is a front elevation of the infant carrier of FIG. 1;

FIG. 7 is a perspective view of an infant carrier, showing a second embodiment of my new design;

FIG. 8 is a top plan view of the infant carrier of FIG. 7; FIG. 9 is a right side elevation of the infant carrier of FIG. 7, the left side being a substantial mirror image except for the protruding tongue and cap rear;

FIG. 10 is a bottom plan view of the infant carrier of FIG. 7;

FIG. 11 is a rear elevation of the infant carrier of FIG. 7;

FIG. 12 is a front elevation of the infant carrier of FIG. 7;

FIG. 13 is a perspective view of an infant carrier, showing a third embodiment of my new design;

FIG. 14 is a top plan view of the infant carrier of FIG. 13;

FIG. 15 is a right side elevation of the infant carrier of FIG. 13, the left side being a substantial mirror image;

FIG. 16 is a bottom plan view of the infant carrier of FIG. 13;

FIG. 17 is a rear elevation of the infant carrier of FIG. 13; and,

FIG. 18 is a front elevation of the infant carrier of FIG. 13.
